(57) **CLAIM**

The ornamental design for a MP3 violin, as shown and described.

DESCRIPTION

FIG. 1 is a perspective view of a MP3 violin showing my new design;

FIG. 2 is a front view thereof;

FIG. 3 is a rear view thereof;

FIG. 4 is a side view thereof;

FIG. 5 is another side view thereof;

FIG. 6 is a top plan view thereof; and,

FIG. 7 is a bottom plan view thereof.

The broken line showing of environment is for illustrative purposes only and forms no part of the claimed design.
